UNITED STATES PATENT OFFICE.

JOSEPH P. B. RAREY, OF KOKOMO, ASSIGNOR OF ONE-THIRD TO STEPHEN P. LEE, OF HOWARD TOWNSHIP, HOWARD COUNTY, INDIANA.

CAR-COUPING.

SPECIFICATION forming part of Letters Patent No. 269,707, dated December 26, 1882.

Application filed October 24, 1882. (No model.)

To all whom it may concern:

Be it known that I, JOSEPH P. B. RAREY, of Kokomo, in the county of Howard and State of Indiana, have invented certain new and useful Improvements in Car-Couplings; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved car-coupling. Fig. 2 is a bottom view of the same. Fig. 3 is a front elevation, and Fig. 4 is a side elevation.

Similar letters of reference indicate corresponding parts in all the figures.

My invention has relation to automatic car-couplings; and it consists in the improved construction, combination, and arrangement of parts, as hereinafter more fully described and claimed.

In the accompanying drawings, the letter A represents a draw-head of the usual construction, and B is the coupling-pin.

To one side of the draw-head, on the platform, is a bearing, C, through which passes a rod, D, which is bent at the upper end, and reaches over to the coupling-pin, to which it is fastened. The lower end of rod D is slotted, as shown at D', and through the slot passes the bent end F' of a rod, F, the other end of which, F², is bent at a right angle to the central part of it, and hung in bearings G on the side of the car.

Under the bearings G is fastened an eye, H, through which slides a rod, I, having a handle on its outer end, and hinged at its inner end to a double crank, J, hung in bearings j, j on the bottom of the car. The outer end of the crank J is bent at a right angle to its straight part, and at an angle of about forty-five degrees to its doubled part or the crank proper, turned a little upward in the outer end, as shown at K, and engages the bent portion F' of the rod F, which slides on its upper side.

L is a bumper on one side of the car, which is fastened on a slide, M, which slides in bearings N, N on the bottom of the car. This slide is doubled parallel to itself, forming a catch for rod F when it is raised. The slide is moved by a crank, O, actuated by a handle, P, the motion from the crank being trans-

ferred to the slide by a pitman, Q, hinged to it. R is the link used. It is of heavy metal, and slightly bent, so as to point in an upward direction when it is placed in the draw-head.

When the coupling is to be used the pin is raised by drawing the rod I out to the side. This turns the crank outward, and arm K lifts the rod F, and consequently the bent rod D, which raises the pin. The slide is brought forward to catch rod F by turning the handle P in the opposite direction. When the car to which it is desired to couple the one where the coupling has been put in order, as above described, comes in contact with the one to be coupled the link will enter the draw-head, being by its shape held a little upward, and the bumper L and slide M are pushed back and release rod F, which allows the pin to drop into place and catch in the link.

The bent end F' of the rod F may be provided with a friction-roller, f', which rolls on the upper surface of the bent arm K. On the upper end of that part of rod D which slides in the bearings C is an elastic buffer, d, which lessens the jar when the coupling-pin is dropped.

Having thus described my invention, I claim and desire to secure by Letters Patent of the United States—

1. In a car-coupling, the combination of the draw-head A, having the coupling-pin B, with the mechanism for operating the same, consisting of the bent rod D, slotted at its lower end, rock-shaft F, having bent end F' inserted through the slotted end of rod D, sliding rod I, and crank J, having bent arm K engaging the bent end F' of rock-shaft F, all constructed and combined to operate substantially as set forth.

2. In a car-coupling, the combination of the mechanism consisting of the bent rod D, slotted at its lower end, rock-shaft F, bent at its free end F', sliding rod I, crank J, having bent arm K, with the sliding bumper L, M, pitman Q, crank O, and handle P, substantially as and for the purpose herein shown and set forth.

In testimony that I claim the foregoing as my own I have hereunto affixed my signature in presence of two witnesses.

JOSEPH P. B. RAREY.
